UNITED STATES PATENT OFFICE

WILLIAM L. ROESSNER, OF DENVER, COLORADO

FIRE EXTINGUISHER

Application filed September 8, 1931. Serial No. 561,666.

This invention relates to improvements in fire extinguishers of the type employing a hermetically sealed glass grenade containing a fire extinguishing liquid, such as carbon tetrachloride, or the like, and has reference more particularly to means for supporting the grenade and for breaking the same when the temperature to which it is subjected exceeds a predetermined value.

One of the objects of this invention is to produce a supporting device for fire extinguishing grenades which shall be so constructed that the same can readily be supported from the wall or from a vertical surface, or from the ceiling of a room.

Another object of this invention is to produce a temperature responsive device that shall become operative, when the temperature rises above a predetermined value, for breaking the grenade, so that the liquid contained therein will be released for the purpose of generating a noninflammable gas that will extinguish the fire.

Another object of this invention is to produce a supporting device of a very simple but substantial construction that can be very easily made at a small cost and which will be especially well adapted for the purpose under consideration.

A still further object of this invention is to produce a fusible link construction that shall positively hold the parts against accidental release until the temperature rises to a predetermined value and in this way prevent the accidental operation of the fire extinguisher.

The above and other objects that may become apparent as the description proceeds, are attained by means of a construction and an arrangement of parts that will now be described in detail and for this purpose reference will be had to the accompanying drawing in which the preferred embodiment thereof has been illustrated, and in which:

Fig. 1 is a side elevation of the fire extinguisher showing the same supported from the ceiling, a portion of the device being shown in section to better disclose the construction;

Fig. 2 is a perspective view of a portion of the device;

Fig. 3 is a perspective view of the hammer;

Fig. 4 is a section taken on line 4—4, 55

Fig. 1;

Fig. 5 is a section taken on line 5—5, Fig. 1, and shows the construction of the fusible links; and

Fig. 6 is a side view of the fusible element.

In the drawing reference numeral 1 indicates the body member of the supporting bracket. This portion of the bracket is adapted to be placed in a vertical position as shown in the drawing, and the upper end thereof is formed into a circle 2 which has an opening for the reception of a glass grenade 3. In the embodiment shown the supporting ring is formed integral with the body member and is bent outwardly at an angle of ninety degrees to the same. Instead of having this ring integral, it may be made from a separate piece, if desired, and attached to the body member in any suitable manner.

The lower end of the body member which has been designated by reference numeral 4 is bent outwardly at an angle so that it will project outwardly and downwardly in the manner shown. The body member is provided near its lower end with a vertical slot 5 through which the reduced portion 6 of the hammer 7 extends. The inner end of the hammer has a transverse portion 8 whose width is substantially equal to the length of the slot and the hammer can therefore be attached to the body member by inserting part 8 through the slot, after which the hammer is rotated through ninety degrees until it assumes a position like that shown in Fig. 1. The free end of the hammer is bent upwardly and then downwardly as indicated by numeral 9 so as to produce a portion of considerable weight that is so positioned with respect to the tip 10 of the grenade that it will strike the latter when the hammer is released in the manner which will

hereinafter be described.

The hammer is provided with downwardly extending projections 11 and the projecting portion 4 has corresponding projections 12 that receive the ends of the tube 13 about

which the coil spring 14 is positioned. The function of the projections 11 and 12 is to hold the spring in position until it has functioned. The tube 13 is not necessary in every case, but it is desirable where a long stiff spring is used because it prevents the spring from bending.

For the purpose of holding the hammer in the position shown in Fig. 1, a novel fusible link anchoring device has been provided. 10 This anchoring device is shown in Figs. 5 and 6, but is not broadly claimed in this application because it forms the subject of a copending application of even date herewith. The anchoring device consists of two flexible 15 arms 15 and 16 which may be formed from a single piece of metal connected at their center points by means of a transverse portion 17. The extreme ends of the arms are bent outwardly as indicated at 18 so as to form divergent portions between which a plug 19 of easily fusible metal can be placed. This plug is preferably inclined at the same angle as the sides 18 and is provided on its edges with depressions 20 for the reception of the 20 portions 18. The outer ends of portions 18 may be bent inwardly as indicated by 21 so as to more securely hold the fusible material in place. When the device shown in Fig. 1 is 25 assembled, arms 15 and 16 are inserted through the openings 22 in part 4, after which they are spread apart and held in spread position by means of the fusible plug. It will be readily seen from Fig. 5 that the 30 hammer is held anchored to the part 4 by means of the fusible link assembly, and that as long as plug 19 remains in a solid state, the arms cannot be withdrawn from the opening. As soon as the temperature rises sufficiently 35 to melt the plug 19, the metal of which this plug is formed, will flow and this will leave the arms 18 without any solid material interposed between them, and therefore they can readily be pulled through the opening, 40 whereupon the spring 14 will function to drive the hammer against the tip 10 of the grenade whereupon the latter will break, and the contents will be discharged into the room.

I want to call particular attention to the 45 link structure shown in Fig. 5 because it will be apparent from this disclosure that there is no danger of this fusible link failing before the temperature has reached the point necessary to fuse the plug. The plug is required to resist compressive strains only and therefore it is very effective because regardless of the fact that the fusible solder of which it is made may not have a very large tensile 50 strength, it will still resist compression as such material is quite solid and has a high coefficient of compressibility and therefore there is no danger of the link failing prematurely as often happens when the ordinary 55 type of link is used in which the tensile

strength of the solder is depended on to hold the link in operative condition.

In large rooms it is often necessary to support some of the fire extinguishers from the ceilings as well as from the walls and from 70 supporting columns, and one of the objects of this invention is to produce a construction that can be readily supported in either position. It will be seen from Fig. 1 that body member 1 is provided with two spaced key-hole slots that have been designated with reference numeral 23 and when the device is to be supported from a wall, two screws or nails are driven into the wall a proper distance apart and inserted in the keyhole slots. 75 When the fire extinguisher is to be supported from the ceiling a bracket 24 is provided. This bracket has a portion indicated by reference numeral 25 which fits against the ceiling and has one or two openings for the 80 reception of securing screws 26. The downwardly extending portion of the bracket is provided with headed pins or rivets 27 that are adapted to pass through the keyhole slots 85 in the manner shown in Fig. 1.

By constructing the support in the manner shown, and by providing brackets 24, it is evident that the fire extinguishers can be supported from either the wall or from the ceiling as may be desired, without necessitating 90 any change in the other parts of the structure, and this greatly simplifies the manufacture, because it makes it unnecessary to provide a 95 separate structure for the wall and for the ceiling.

Having described the invention what is claimed as new is:

1. In a fire extinguisher of the type employing a hermetically sealed glass grenade containing a fire extinguishing liquid, such as, carbon tetrachloride, a bracket having a vertically disposed body member, the upper end of the body member having a grenade supporting means adapted to hold a grenade with its tip projecting downwardly, 105 the lower end of the body member being bent so as to project outwardly therefrom, a hammer having its inner end pivotally attached to the body member above the bend, a compression coil spring located between the hammer and the outwardly projecting portion of the body member, a tubular member located inside of the spring for preventing buckling thereof, and a fusible link extending between the hammer and the outwardly bent portion for holding the hammer in such a position that the spring will be under compression whereby when the temperature rises sufficiently to make the link fail the hammer 110 will move in response to the action of the spring and break the grenade.

2. A bracket for supporting a hermetically sealed glass grenade containing carbon tetrachloride or the like, comprising a substantially straight body member of sheet 130

metal adapted to be supported in a vertical position, means for supporting a grenade located adjacent the upper end of the body member, the lower end of the body member being bent along a transverse line so as to extend outwardly at an angle to the upper portion of the body member, the body member having a narrow vertical slot positioned a short distance above the bend, an elongated hammer comprising a flat metal strip having an enlarged striking head at one end and a neck portion of reduced width at the other end, the length of the slot being sufficient to permit the end of the hammer having the neck portion to be inserted when its plane is parallel to the plane of the slot, the width of the slot being slightly greater than the width of the neck portion whereby when the hammer is rotated into a plane perpendicular to the length of the slot it will not come out of the slot, a coil compression spring located between the hammer and the outwardly bent portion of the body member and a fusible link connecting the outer end of the hammer with the outer end of the outwardly inclined portion of the body member.

In testimony whereof I affix my signature.

WILLIAM L. ROESSNER.
